UNITED STATES PATENT OFFICE.

OSCAR H. WISENANT, OF COLORADO SPRINGS, COLORADO.

AEROPLANE WING.

Application filed May 10, 1920. Serial No. 380,250.

To all whom it may concern:

Be it known that I, OSCAR H. WISENANT, citizen of the United States, residing at Colorado Springs, in the county of El Paso and State of Colorado, have invented certain new and useful Improvements in Aeroplane Wings; and I do hereby declare the following to be a full, clear, and exact description of the invention, such as will enable others skilled in the art to which it appertains to make and use the same.

This invention relates to new and useful improvements in aeroplane wings and more particularly to an aeroplane wing whereby the vacuum lift can be increased. It is a well-known fact in the science of aviation that the greatest lift is derived from the vacuum suction on the upper side of the aeroplane wing, this lift being about 87% greater than the pressure on the bottom side. It is, therefore, the main object of my invention to provide means for increasing this vacuum lift nearly 100% by the use of my improved concave upper side wings.

A further object of the present invention is the provision of an aeroplane wing provided with an increased concave surface which is adaptable to the form and shape of wing used at the present time without changing the accepted curvature of the wings now in use.

A further object of the present invention is the provision of an increased vacuum lift in the general construction of aeroplane wings without adding resistance as the original curvature of the wing is not altered in any way whatever.

A still further object of this invention is the provision of an increased concave surface for the upper side of an aeroplane wing which will not interfere with the action of the ailerons or with the air currents, generally termed "wash-outs", that act upon the outer ends of aeroplane wings.

With the above and other objects in view, the invention consists in the novel features and construction, the combination and arrangement of parts hereinafter more fully set forth, pointed out in the claims and shown in the accompanying drawings, in which—

Figure 1 is a perspective view of a frame of an aeroplane wing, constructed in accordance with my invention,

Figure 2 is a perspective view of the completed wing, and

Figure 3 is a side elevation, showing the increased vacuum at the side of the wing.

In carrying out my invention, I provide a frame which is generally indicated in perspective in Figure 1 and which includes a plurality of cross-pieces generally indicated by the numeral 1. These cross-pieces are connected at their ends by means of the longitudinal strips 2 and further connected at a point adjacent their central portion by means of the strips 3, said strips being secured to the top portion of the cross-pieces 1 in any suitable manner. In the construction of the frame, certain of the cross-pieces, preferably the ones arranged at the end of the frame and at the central portion thereof are provided with arcuate outer surfaces as indicated at 4. In the present construction of the frame which is herein illustrated, the end piece 5 is disposed at an angle with respect to the other cross-pieces to give the desired shape to the wing when it is completed. In the central portion of the wing, there are two cross-pieces indicated by the numeral 6, which are provided with arcuate outer faces to correspond with the curvature of the upper side of the wing.

In order to provide for a vacuum lift in the top of the wing, the cross-pieces 7 are cut-away or concaved centrally of their upper edges as shown at 8. These cross-pieces 7 are arranged in sets upon opposite sides of the center of the wing so that when the canvas or other covering material is arranged over the frame, suitable pockets 9 are formed in the upper face of the wing and disposed upon opposite sides of the center thereof as illustrated in Figure 2. From this it will be apparent that a vacuum lift is provided that can be added to the general type of aeroplane wing without changing the present accepted curvature and which will increase the vacuum lift to a great extent.

In Figure 3, I have illustrated a slightly modified form of the invention, wherein the cross-pieces are each formed in sections, suitably connected together by strips 10 arranged upon the opposed faces of the cross-pieces whereby to suitably connect the various sections 11 together. It will be noted that the several sections are arranged in spaced relation to provide for openings 12, thus decreasing the weight of the wing. The end sections 13 are arranged between the ends of the strips 10 and suitably secured

2
thereto in any desired manner. It will be apparent from the foregoing that this increased vacuum lift can be secured without adding resistance as the original curvature of the wing is not altered in any way whatever and does not interfere with the action of the ailerons or of the air currents, which are termed "wash-outs," that act upon the outer ends of all aeroplane wings.

10 What I claim is:

1. An aeroplane wing of the class described including a frame, comprising cross-pieces, said cross-pieces being intermediate the ends and center of the wings having concave portions cut in their upper faces intermediate their ends and a cover arranged over said frame having portions thereof disposed within to conform with the concave
- 15

portions of the cross-pieces whereby to provide pockets upon opposite sides of the center of the frame.

2. An aeroplane wing having a concave under surface and a convex upper surface except for a plurality of longitudinally extending and longitudinal spaced concave pockets said pockets provided with substantially perpendicular end surfaces.

3. In an aeroplane wing a pocket formed in one face extending longitudinally of the wing but of less length than the wing, said pocket concaved relative its longitudinal axis and having end faces substantially perpendicular to the plane of the wings.

In testimony whereof I affix my signature.

OSCAR H. WISENANT.
